DRUM BEATER

Bruce W. Dane, Cranford, N. J.

Application April 30, 1956, Serial No. 581,672

6 Claims. (Cl. 84—422)

This invention relates to drum beaters and more particularly to a novel arrangement for securing the beater head to the handle.

A drum beater comprises a generally spherical or cylindrical head, made of felt or other suitable material, carried at one end of a slender, resilient handle. Heretofore, the head has been secured to the handle by various arrangements utilizing a screw threaded into an axial hole in the handle, bolts and nuts, cement, etc. In use, a drum beater is subject to vigorous pounding and one of the problems has been to devise a satisfactory means whereby the head will remain securely affixed to the handle throughout the normal life of the device. In this respect cement and threaded-cooperating parts have been found to be inadequate.

An object of this invention is the provision of a novel arrangement for securing the head of a drum beater to the handle and which arrangement is of such character as to retain the head firmly secured to the handle under all conditions of use.

An object of this invention is the provision of a drum beater wherein the resilient head is compressively clamped between spaced washers, the spacing between said washers being fixed by a spring member secured to the handle.

An object of this invention is the provision of an arrangement for securing a head of resilient material to a handle to form a drum beater, said arrangement comprising a lower, cup-like washer affixed to the handle, a generally U-shaped spring having divergently-offset ends disposed in radially aligned holes formed in the handle, and an upper, cup-like washer secured in position by the central portion of the spring, the said head being compressively clamped between the said cup-like washers.

An object of this invention is the provision of a drum beater comprising a handle having a tapered end, an axial bore in the tapered end of the handle said bore communicating with radial holes formed in the handle wall; a lower, cup-like washer having a central hole and inserted over the tapered end of the handle to a predetermined, maximum extent; a generally spherical head of resilient material having a central hole extending therethrough, said head being inserted over the tapered end of the handle; a U-shaped spring wire having its ends offset in opposite directions, the arms of said wire passing into the said axial bore and the offset spring ends extending into the said radial holes; and an upper cup-like washer secured in position by the said wire, the spacing between the said cup-like washers being less than the normal thickness of said head whereby the head is compressively clamped between the two washers.

These and other objects and advantages will become apparent from the following description when taken with the accompanying drawings illustrating a drum beater made in accordance with this invention. It will be understood, however, that the drawings are for purposes of illustration and are not to be construed as defining the scope or limits of the invention, reference being had for the latter purpose to the appended claims.

In the drawings wherein like reference characters denote like parts in the several views:

Figure 1 is an exploded view, with parts in section,

2

showing the components of a drum beater made in accordance with this invention;

Figure 2 is a plane view of the upper, cup-like washer showing the radial notches extending from the central hole of the washer;

Figure 3 is similar to Figure 2 and showing the stud assembled with the washer, with the slot of the stud head aligned with the radial notches formed in the washer;

10 Figure 4 is a fragmentary view showing a partial assembly, that is, showing the lower-cup-like washer, the head and the retaining spring wire assembled on the tapered end of the handle;

Figure 5 is a central, cross sectional view, drawn to 15 an enlarged scale, showing the completed assembly of the head on the handle;

Figure 6 is an elevation showing the completed drum beater; and

Figure 7 is a central, sectional view showing the U- 20 shaped spring wire carried by an upper cup-like washer of somewhat different construction.

Reference is now made to Figure 1 wherein there is shown a slender handle 10 made of fiber glass, hard wood or any other material strong enough to retain the 25 compressed head assembly. The upper end of the handle is tapered and is provided with an axial bore 11 intersected by a transverse hole to form the radial holes 12, 12'. The main portion of the handle has a diameter such as will provide the required degree of resiliency for use 30 of the beater. In accordance with conventional practice, a ball 13, made of wood or plastic, is secured to the lower end of the handle such ball retaining a suitable spring, or hook, 14 to which a conventional thong may be attached. A lower, cup-shaped washer 15 is carried by the 35 tapered end of the handle. The washer is so formed that the material around the central hole is pressed inwardly to form an integral collar 16 and the diameter of the hole is such that the washer can be forced along the tapered portion of the handle to a predetermined position. Also, 40 the peripheral surface of the washer is provided with a plurality of teeth 17 for purposes which will be described hereinbelow.

The beater head 18 may comprise an inner member 19 of relatively hard felt, cork or other compressible material, enclosed within a covering 20 of relatively soft felt. Such head is of generally cylindrical, or truncated spherical, form and is provided with a central hole 21 extending therethrough. I prefer to make the diameter of the hole 21 correspond to the minimum diameter of handle 45 thereby requiring a certain amount of force to insert the tapered handle end into the head. An upper cup-like washer 22 corresponds in external appearance to the lower washer 15. However, the upper washer 22 is formed to accommodate the head of a stud 23 and for this purpose the inwardly-bent central portion of the washer is formed with a circular lip 24. A generally U-shaped spring 25, made of music wire or the like, has a base portion 26, diverging arms 27, 27' and reversely offset ends 28, 28'. The base portion of the spring is 50 adapted to fit into a conventional, diametrical slot formed in the head of the stud 23. It may here be pointed out that in the assembled device the head of the stud 23 fits nicely within the reversely-formed well formed in the upper washer 22. Consequently, in order to accommodate those portions of the spring base which extend beyond the stud head, the washer 22 is provided with diametrically-opposed slots or notches 30 as shown in Figure 2. Thus, when the stud is positioned on the washer, as shown in Figure 3, the slot 31 in the stud head 23 can 55 be aligned with the slots 30 in the washer and the linear length of the combined slot and notches is slightly longer than the dimension "a" of the spring.

In the assembly of the drum beater, the lower washer 15 is first inserted to the fullest extent on the tapered end of the handle. Next, the arms 27, 27' of the spring are pinched together, as with the fingers, and inserted into the axial bore 11 in the handle until the offset spring ends 28, 28' snap into the radial holes 12, 12'. Such insertion of the spring into the operative position is done while the head is detached from the handle. Consequently, the radial holes in the handle are visible to the operator whereby the spring can be easily and accurately placed into proper position. The base dimension "a" of the spring is slightly less than the diameter of the hole in the head 18 so that the head can now be forced over the tapered portion of the handle with the spring in position as described.

The sub-assembly of the lower washer 15, head 18, and spring 25 is shown in Figure 4. It will be noted that the base of the spring is disposed below the upper surface of the head. The purpose for such arrangement is to obtain a substantial compression of the head in the completed device, as will now be described. The sub-assembly shown in Figure 4 is placed in a suitable press, such as an arbor press, that is provided with a suitable fixture for supporting the sub-assembly in the vertical position as shown in Figure 4. More specifically, the fixture includes a hole through which passes the handle 10 and the upper surface of the fixture is of concave form to support and position the lower washer 15. The press is provided with a hollow plunger having a concave working end conforming to the arcuate contour of the outer surface of the upper washer 22, see Figure 1. Such upper washer is now placed on the head 18 with the slots 30 (see Figure 2) aligned with the base portion 25 of the spring. As the plunger is lowered under pressure, the head 18 is compressed between the lower washer supported by the fixture and the upper washer being forced downwardly by the press. The head is compressed until the base portion of the spring passes through the slots in the upper washer and beyond the upper surface of same. It is here pointed out that portions of the side wall of the compressing plunger are cut away so that operator can observe the central portion of the upper washer and the spring base during this operation. With the base of the spring so protruding beyond the upper surface of the head, the stud 23 is now dropped into the concave central well of the upper washer, and the stud rotated by hand with a suitable tool until the slot in the stud head is aligned with the base portion of the spring. When this is done the operator slowly releases the pressure generated by means of the press whereby the head 18 tends to expand to its original form. As shown in Figure 5, the extent of expansion of the head is restricted by the upper washer 22 that is now held in position relative to the handle 10 by the offset ends 28, 28' of the spring. The parts are so dimensioned that the assembled head is retained under considerable compression and actual tests have shown that the head so assembled cannot become separated from the handle under the most severe conditions of use.

In order to prevent possible rotation of the head about the handle a suitable cement may be applied to the tapered end of the handle just prior to the assembly of the head thereon. Also, the lower washer 15 is provided with a plurality of peripheral teeth 17 (see Figure 1) which bite into the lower surface of the head thereby preventing relative rotation between the head and the handle, it being apparent that the lower washer is tightly secured to the handle by reason of its being forced to the fullest extent possible on the tapered handle.

As shown in Figure 6, the drum beater is of pleasing appearance. The head of the stud and the base portion of the wire spring lie in a well below the outer surface of the upper washer 22. The handle does not protrude beyond the upper surface of the head and there are no exposed screws, nuts, or etc., as found in drum beaters

made heretofore. The outwardly symmetrical washers 15 and 22 are made of polished, hard aluminum or nickel-plated steel which actually enhances the overall appearance of the device.

In the above described arrangement the upper washer 22 is locked in position with respect to the spring and handle by means of the stud having a head disposed within the well formed in the washer. Such specific construction is not essential to the practice of the invention. Figure 7 illustrates a washer 33 of somewhat different form and which eliminates the need for a cooperating stud. Here, the central portion of the washer is pressed inwardly and two holes 34, 35 are punched in the lower surface 36 of the so-formed well. In this case, the holes must be of sufficient diameter so that the offset ends 28, 28' of the wire spring can be passed therethrough and the spring must be inserted into the axial hole in the handle with the washer 33 so assembled to the spring. Further, the spring must be inserted into the handle with the head of the beater in place and under pressure, which renders the assembly operation less convenient.

Having now described my invention those skilled in this art will find no difficulty in making changes and modifications in the form of the individual parts and in the assembly thereof to meet specific conditions. Such changes and modifications may be made without departing from the spirit and scope of the invention as recited in the following claims.

I claim:

- 30 1. An arrangement for securing a resilient head to a handle to form a drum beater, said arrangement comprising a tapered end on the handle, said end being provided with an axial bore communicating with radially extending holes; a lower washer force-fitted on the said tapered end of the handle; an upper washer secured to the handle by means of a spring having arms extending into the said axial bore and offset ends disposed within the said radial holes, the tapered end of said handle being inserted into a hole provided in said head and said head being compressively clamped between said washers.
- 35 2. The invention as recited in claim 1, wherein the washers are of arcuate form and reversely disposed to each other, and the said lower washer includes peripheral teeth.
- 40 3. The invention as recited in claim 1, wherein the said upper washer is provided with a reversely disposed central wall having diametrically opposed slots therein, a stud passing through the washer and having a head disposed within the well formed by said reversely disposed wall, and the central portion of the spring is disposed within the said slots and an aligned slot formed in the head of the stud.
- 45 4. The invention as recited in claim 1, wherein the tapered end of the handle extends only partially through the hole in the head.
- 50 5. A drum beater comprising a handle having a tapered end provided with an axial bore communicating with a pair of radial holes; a lower washer force-fitted on the tapered end of the handle; a head of resilient material having a hole passing therethrough and inserted over the said tapered end of the handle with the lower surface of the head abutting the said lower washer; an upper washer abutting the upper surface of the head, said washer being provided with a central well; a stud having a slotted head disposed in said well; and a wire spring having a base portion disposed within the slot in the stud head, a pair of normally diverging arms extending into the handle bore and offset ends disposed within the said radial holes, the spacing of said washers being less than the normal thickness of said resilient head.
- 55 6. The invention as recited in claim 5, wherein the said washers are of arcuate form and reversely disposed, and the lower washer includes peripheral teeth.
